UNITED STATES PATENT OFFICE.

LESTER KELLER, OF FIRE CREEK, WEST VIRGINIA.

FOLDING CHAIR.

SPECIFICATION forming part of Letters Patent No. 399,049, dated March 5, 1889.

Application filed August 15, 1888. Serial No. 282,776. (No model.)

To all whom it may concern:

Be it known that I, LESTER KELLER, a citizen of the United States, residing at Fire Creek, in the county of Fayette and State of West Virginia, have invented a new and useful Improvement in Folding Chairs, of which the following is a specification.

The object of this invention is to provide a simple, cheap, and durable folding chair; and it consists in a certain novel construction and arrangement of devices fully set forth herein-after in connection with the accompanying drawings, and specifically pointed out in the appended claims.

In the drawings, Figure 1 is a perspective view of a chair embodying my improvements. Fig. 2 is a detail view. Fig. 3 is a side view of the same in its folded position. Fig. 4 is a detail view of the foot-rest.

Referring by letter to the drawings, A designates the seat of the chair, having the side bars, B B, to the inner sides of which, near their front and rear ends, respectively, are pivoted the front and rear legs, C C and C' C', and the front legs and the rear legs are respectively connected together by suitable cross-bars, c and c', near their upper ends, and also by similar cross-bars near their lower ends.

To the inner sides of the side bars, B B, near or at their centers, are pivoted the swinging braces D D', which are provided at their free ends in their lower edges with notches d and d', which are adapted to be engaged with the upper edges of the cross-bars c and c', respectively.

E represents the leg-rest, which is provided with the side bars, F F, and the side bars are extended beyond the inner end of the rest to form ears f f, which are pivoted to the ears b b, formed by a forward extension of the side bars, B B.

G G represent swinging clutches pivoted to the front legs of the chair and provided at their lower ends with longitudinal slots g, and H H represent curved arms which are pivoted to the rear side bars of the leg-rest and operate at their free ends in the slots g. These slots g are slightly longer than the width of the curved arms, and therefore when the clutches

swing downward and assume a position at an angle to the curved arms the latter are clamped tightly by the slots, and to adjust the curved arms in the slots it is necessary to raise the clutches until they are at right angles to the 55 arms. The lower ends of the clutches G G are connected by the rod G', whereby both clutches may be operated from one side of the chair.

I designates the back of the chair, provided with the side bars, K K, which are extended below the lower edge of the back, and are provided with pins k k, mounted in longitudinal slots L L near the rear ends of the bars of the seat, the said slots being provided at their 65 ends with enlargements l, in which the pins normally rest.

Clutches M M (similar to the clutches G G) are mounted on the rearwardly-extending ends of the side bars, B B, and are provided 70 with slots m m, in which operate the free ends of the curved arms N N, which are pivoted to the side bars, K K, at about their central points.

The side arms, O O, are pivoted at their 75 rear ends to the side bars of the back, near their lower ends, and are connected at their front ends to the side bars of the seat by the links P P, which are provided at their lower ends with pins p p, operating in longitudinal 80 slots Q Q in the side bars, B. The slots Q Q are preferably formed below the lower edge of the side bars, near their front ends, by providing the latter with an offset, Q', while the slots L L are preferably formed above the upper 85 edges of the side bars, near the rear ends, by providing the latter with offsets L'.

To fold the chair, disengage the braces from the cross-bars of the legs and fold the latter against the under side of the seat by 90 passing the front legs between the rear legs, then disengage the curved arms H H from the clutches G and fold the leg-rest on the upper side of the seat, then disengage the curved arms N N from the clutches M, draw the pins 95 on the lower ends of the side bars of the back rearwardly to the ends of the slots L and fold the back over the leg-rest, thus folding the chair into a compact and portable form. When the back is in its operative position, 100

the pins on the lower ends of its side bars are arranged at the front ends of the slots L, so that when the back is horizontal (flush with the bottom) its lower or inner edge will be arranged close to the rear edge of the bottom. When the back is folded forward on the seat, the pins on its side bars are arranged in the rear ends of the slots L, in order to enable the back to lie on the seat without projecting beyond its front edge. (Clearly shown in Fig. 3.) The lower ends of the links P (which connect the front ends of the side arms to the chair-seat) are arranged at any points of the slots Q to suit the position of the back and to hold the side arms at the desired height. When the back is folded on the seat, the lower ends of the said links are arranged at the rear ends of the slots.

R represents a foot-rest which is attached to the lower end of the leg-rest, and it is provided with hooks s s, which are engaged with transverse pins S', arranged between the side bars, S, and turned down to form the standards T T, which may rest on the floor when the chair is in its operative position.

The back, seat, and leg-rest of this chair are preferably formed of cane or a similar material.

It will be obvious from the foregoing description that the back of the chair may be arranged at any desired angle to the seat from parallel therewith to perpendicular thereto. When parallel or in the same horizontal plane with the seat, the lower ends of the side bars of the back pass on opposite sides of the seat; and the inner (or lower) edge of the back comes close to the rear edge of the seat,

hence the object in extending the side bars of the back beyond (or below) the inner (or lower) edge of the back; but when the chair is folded the lower ends of the said side bars must be arranged at the rear ends of the slots L, in order that the back may fold on and coincide with the seat.

Having thus described my invention, I claim—

1. In a folding chair, the combination, with the seat provided near its rear edge with horizontal slots L L, of the back having side bars, K, which extend below its lower edge and are provided with pins which slide in the said slots, whereby when the back is in a horizontal position its edge fits close to the rear edge of the seat, and the swinging arms attached to the back and engaged by suitable clutches, substantially as specified.

2. In a chair, the combination, with the seat provided with the side bars, B B, having slots L L near their rear ends and slots Q Q near their front ends, of the back having side bars provided with pins mounted in the slots L L, the swinging arms on the back engaged by clutches on the seat, the side arms pivoted at their rear ends to the back, and the links connected to the front ends of the arms and having pins on their lower ends operating in the slots Q Q, substantially as specified.

In testimony that I claim the foregoing as my own I have hereto affixed my signature in presence of two witnesses.

LESTER KELLER.
